THEODORE SMITH, OF CHICAGO, ILLINOIS.

BRACKET FOR ELECTRIC LIGHTS.

SPECIFICATION forming part of Letters Patent No. 759,925, dated May 17, 1904.

Application filed July 27, 1903. Serial No. 167,084. (No model.)

To all whom it may concern:

Be it known that I, THEODORE SMITH, a citizen of the United States of America, residing at Chicago, in the county of Cook and State 5 of Illinois, have invented certain new and useful Improvements in Brackets for Electric Lights, of which the following is a specification.

My invention relates to certain improvements in brackets for electric lights, the object of which is to provide a bracket affording a universal adjustment of the position of the light with respect to its point of support, said bracket to contain an electric cord, in- 15 closing the same without endangering it in the movements of the joints of the bracket.

The invention consists in various features of novelty which will appear in the detail description and which will be pointed out more 20 definitely in the claims.

In the drawings, Figure 1 is a side elevation of the bracket, shown as secured to a wall and carrying a lamp, socket, and shade. Fig. 2 is a longitudinal median section of the 25 bracket, showing portions broken away to reduce the length of the figure. Fig. 3 is a horizontal section looking downward upon the plane 3 3 of Fig. 2 and disclosing the means for preventing the separation of the 30 two members jointed together at that point. Fig. 4 is a horizontal section looking downward upon the plane 4 4 of the same figure and disclosing the means for preventing the continued rotation of one member upon the 35 other, which would be liable to break the cord. Fig. 5 is a detail end elevation of a clamp which bears upon the two parallel arms of the bracket. Fig. 6 is a horizontal section through said clamp looking down upon the 40 plane 6 6 of Fig. 5, and Fig. 7 is a perspective view of the universal joint between the free end of the bracket and the lamp-socket.

Referring to the drawings, A represents the wall, upon which is secured two vertically- 45 perforated clamps B C, provided with set-screws b c. In these clamps is secured a vertical portion d of the curved lower member D of the first section of the bracket, the main portion of said member being shown as curved 50 upward abruptly near said clamps at d', and

then curved reversely at d'', thereafter gradually approaching the upper member, as at d', and being secured against rotation in a block E by means of a pin e. The upper member F of the first section of the bracket 55 is shown as tubular and is also secured in the block E. Adjacent to the wall it is connected to the lower member D by means of a T-coupling f, fastened to the member D by a set-screw f'. The side of this T-coupling opposite the member F is slit at f'', (see Fig. 2,) so that the electric cord X may be inserted in line with the tubular member F. A perforated bushing G is threaded in the top of the T-coupling, and after the insertion of the 60 cord in the bracket this bushing is slipped over the cord and screwed into the coupling, so as to complete the tubular form of the coupling. The block E is provided with a vertical tubular post e', (see Fig. 2,) upon which 65 the second section of the bracket is pivoted, and it should be noticed that the construction of the first as described gives it great rigidity. The lower member D securely prevents the joint from sagging, and by reason 70 of its rigid connection with the block E and its vertical integral portion d it offers great resistance to twisting or springing of the joint when the second joint is arranged at right angles thereto. This first section is readily 75 assembled with the wall-clamps B C by loosening the set-screw f' and separating the two members at this point sufficiently to permit the clamps to be slipped upon the vertical portion of the lower member. The block E is 80 provided with an opening e' in line with the tubular member F, so that the cord may be slipped directly through said tubular member and extend from this opening before turning it upward through the post e'. A pivotal 85 connection upon a vertical axis between the first and second joints of the bracket is provided by placing upon the post e' a coupling or clamp G', perforated at g to receive the post and slit upon one side g' and provided 90 with a clamping-screw g'', by means of which it may be tightened upon said post. A circumferential groove e' upon the post and a screw g''' (see Fig. 3) working in said groove 95 prevents the lifting of the clamp from the 100

post when otherwise loose and free to rotate thereon. Upon the side of the clamp G' opposite the clamping-screw is a lug g^4 and a short distance beneath it are two ears $g^5 g^6$, one of which is in view in Fig. 1, the other in Fig. 2, and a small portion of each in Fig. 4. Between these ears is pivoted one end of a rod H , and upon the lug g^4 is pivoted one end of a tube I by means of a forked end 10 piece i , which embraces the lug. Said lug g^4 is perforated at g^7 to receive the cord X , and it should be noticed that the slit in the clamp G' is directly opposite this perforation, so that in threading the cord in the bracket access to the perforation is afforded in a direct line. The tube I and the rod H are arranged in parallel positions and both are embraced by a clamp J , consisting of two portions $j j'$, (see Fig. 5,) of which the part j' is preferably 20 provided with a biting-rib j'' . (Seen in dotted lines in Fig. 5 and shown in full lines in Fig. 6.) A notch i'' is preferably provided in the tube I to receive the rib j'' and prevent longitudinal movement of the clamp upon the tube. 25 The friction of the parts is relied upon to prevent the longitudinal movement of the rod H through the clamp. By adjusting the clamping-screw the desired amount of resistance to such motion can be obtained, which should 30 be just sufficient to support the load placed upon the bracket securely, so that by the application of slight force this arm of the bracket may be moved up or down. The upper face of the block E is provided with two shoulders $e^x e^y$, 35 and between said block and the clamp G' is placed a washer K , having a tongue k , projecting radially and extending downward between the shoulders $e^x e^y$. Shoulders are also provided upon the ears $g^5 g^6$ of the clamp G' , ex- 40 tending downward sufficiently to engage with said tongue of the washer, but not quite reaching the shoulders upon the block E . Said shoulders upon the block E act as stops to limit the rotary movement of the washer with 45 respect to the block, and the tongue of the washer serves as a stop, which engages with the shoulders upon the ears $g^5 g^6$ to limit the rotation of the clamp with respect to the washer. All of said shoulders, as well as the 50 tongue of the washer, are so proportioned as to permit the parallel arms $I H$ to be swung around into the plane of the members $F D$, so as to give the parallel members a movement 55 throughout a complete circle upon the first section of the bracket. This could not be accomplished with stops or shoulders merely upon the two portions of the joint. The material necessary to form the shoulders would necessarily reduce the extent of such movement. 60 As before stated, the washer forms a stop for one part of the joint and has a movement upon the other part of the joint sufficient to compensate for the necessary material of the stop. The outer ends of the tube 65 H and rod I are both pivoted to a hollow

knuckle M , (see Fig. 7,) provided with two downwardly-projecting legs $m m'$, two horizontally-projecting ears $m^2 m^3$, opposite perforations $m^4 m^5$ in the central portion of the knuckle, similar perforations $m^6 m^7$ in the ends 70 of the legs, and similar perforations $m^8 m^9$ in the ears. The tube I has a forked end piece i^2 , which is pivoted to the knuckle by means of two screws $i^3 i^4$. The end of the rod H is pivoted to the knuckle by means of a screw 75 h , and the knuckle itself is preferably made of two parts $M' M^2$, as shown in Fig. 7, the part M^2 comprising the ear m^3 and the inner portions of the legs $m m'$ and being held in place by the pivotal connections with the other 80 members. A second hollow knuckle N has two ears $n n'$, pivoted between the ears $m^2 m^3$ by means of screws $n^4 n^5$. It also has two ears $n^6 n^7$ extending in the opposite direction and arranged in planes at right angles to the ears 85 $n n'$, and a socket-holder O is pivoted to said ears by means of screws $o o'$, the latter being provided with a flat head o^2 to serve as a clamping-screw to clamp the socket-holder 90 against vertical oscillation. The socket-holder is provided with an ordinary hollow post o^3 to support the lamp-socket and receive the electric cord. It should be noticed that the knuckle N has a limited swing upon the knuckle M and that the socket-holder O has 95 shoulders o^4 , which limit its swing upon the knuckle N . The motion allowed to these knuckles is ample for the movement required for this joint; but it is not sufficient to permit of the straining of the wire or the breaking of 100 the insulation.

Throughout the extent of the bracket the cord is guarded at every point against undue flexure and consequent wearing away in the use of the bracket. The middle joint—for instance, where the clamp G' of the second section turns upon the post e' of the first section—is offset to a sufficient extent to give the vertical portion of the cord the necessary length to avoid too sharp a twist as the two 110 sections swing one upon the other.

I have claimed herein only the general construction of my improved bracket, the particular construction of the cord supporting and carrying parts being claimed in another application filed December 22, 1903, and allotted Serial No. 186,226.

I recognize the fact that great variation in construction is possible and that the different portions of the bracket herein described are 120 capable of use with other members differing widely from those of the complete structure herein described. I do not limit myself, therefore, to the specific construction shown nor to the combinations of one part with another, 125 except as the same are essential to the inventions set forth in the following claims.

I claim as new and desire to secure by Letters Patent—

1. In a bracket of the class described, the 130

combination with a vertically-disposed supporting device adapted to be secured to a wall, of a swinging arm supported by said device and composed of two members secured together at their outer ends, the lower of said members having an integral vertical portion extending from below upward through the supporting device and the upper of said members extending from the point of connection between the two members to a point above the supporting device and there connected to the upper end of the vertical portion of the lower member.

2. In a bracket for electric lights, the combination with a supporting device adapted to be attached to the wall, of a swinging arm comprising an upper and a lower member connected at their outer ends, said lower member having a vertical portion passing through the supporting device, said upper member extending from the point of connection to a point above said supporting device, and a T-coupling having its lateral boss secured upon the end of the upper member and its longitudinal tubular portion clamped upon the upper end of the vertical portion of the lower member.

3. In a bracket of the class described, the combination with a suitable supporting device for attachment to a wall, of a swinging arm comprising an upper and a lower member secured together at their outer ends by means of a connecting device, which is secured

against rotation upon the lower member and is itself adapted to serve as a support for other devices, said lower member having an integral vertical portion secured in the supporting device, said upward member extending from the connecting device to a point above the supporting device and a T-coupling having its lateral boss secured to the upper member and its longitudinal tubular portion clamped upon the upper end of the vertical portion of the lower member.

4. In a jointed bracket, the combination with two sections pivoted together and provided with shoulders, of means for limiting the motion of one section with respect to the other, comprising a piece adapted for engagement with the shoulders upon both members and movable with respect to both sections.

5. In a jointed bracket, the combination with two pivoted sections, of means for limiting the pivotal motion of one upon the other, comprising a piece movable with respect to both sections, and provided with means of engagement therewith.

In witness whereof I have signed the above application for Letters Patent, at Chicago, in the county of Cook and State of Illinois, this 23d day of July, A. D. 1903.

THEODORE SMITH.
